Primary Examiner—Terry A. Wallace

(74) Attorney, Agent, or Firm—Mark Kusner; Michael A. Jaffe

(57) **CLAIM**

The ornamental design for the coffee preparation set, as shown and described.

DESCRIPTION

FIG. 1 is a perspective view of a short handled spoon component of the set showing one aspect of my new design; FIG. 2 is a front view of the short handled spoon; FIG. 3 is a right side view of the short handled spoon; FIG. 4 is a top view of the short handled spoon; FIG. 5 is a rear view of the short handled spoon; FIG. 6 is a bottom view of the short handled spoon; FIG. 7 is a left side of the short handled spoon;

FIG. 8 is a perspective view of the long handled spoon component of the set;

FIG. 9 is a front view of the long handled spoon;

FIG. 10 is a right side view of the long handled spoon;

FIG. 11 is a top view of the long handled spoon;

FIG. 12 is a left side view of the long handled spoon;

FIG. 13 is a rear view of the long handled spoon;

FIG. 14 is a bottom view of the long handled spoon;

FIG. 15 is a perspective view of the bag closure component of the set;

FIG. 16 is a top view of the bag closure;

FIG. 17 is a left side view of the bag closure;

FIG. 18 is a rear view of the bag closure;

FIG. 19 is a front view of the bag closure;

FIG. 20 is a right side view of the bag closure;

FIG. 21 is a bottom view of the bag closure;

FIG. 22 is a perspective view of the tongs component of the set;

FIG. 23 is a top view of the tongs;

FIG. 24 is a left side view of the tongs;

FIG. 25 is a rear view of the tongs;

FIG. 26 is a front view of the tongs;

FIG. 27 is a right side view of the tongs;

FIG. 28 is a bottom view of the tongs;

FIG. 29 is a perspective view of the short brush component of the set;

FIG. 30 is a left side view of the short brush;

FIG. 31 is a front view of the short brush;

FIG. 32 shows the bottom and top view of the short brush;

FIG. 33 is a rear view of the short brush;

FIG. 34 is a perspective view of the long brush component of the set;

FIG. 35 is a left side view of the long brush;

FIG. 36 is a front view of the long brush;

FIG. 37 shows the bottom and top view of the long brush;

FIG. 38 is a rear view of the long brush;

FIG. 39 is a perspective view of the espresso coffee tamper component of the set;

FIG. 40 is a side view of the tamper;

FIG. 41 is a top view of the tamper;

FIG. 42 is a front and rear view of the tamper; and,

FIG. 43 is a bottom view of the tamper.

The individual pieces of the set are shown separately for clarity of illustration.
